[57] CLAIM

The ornamental design for a motorcyclist's safety belt, as shown and described.

DESCRIPTION

FIG. 1 is a top perspective view of a motorcyclist's safety belt showing our new design;
FIG. 2 is a side elevational view thereof;
FIG. 3 is a top plan view thereof;
FIG. 4 is an end elevational view as taken from line 4—4 of FIG. 3;
FIG. 5 is a top perspective view of another embodiment of our new design of FIG. 1;
FIG. 6 is a side elevational view thereof;
FIG. 7 is a top plan view thereof.
